UNITED STATES PATENT OFFICE

141,910

DESIGN FOR A PORTABLE BARBECUE OR SIMILAR ARTICLE

John Shirley Ward, Pasadena, Calif., assignor to
A. C. Mfg. Co., Van Nuys, Calif., a corporation of California

Application March 5, 1945, Serial No. 118,276

Term of patent 14 years

(Cl. D81—10)

To all whom it may concern:

Be it known that I, John Shirley Ward, a citizen of the United States residing at Pasadena, in the county of Los Angeles and State of California, have invented a new, original, and ornamental Design for Portable Barbecue or Similar Article, of which the following is a specification, reference being had to the accompanying drawings forming a part thereof.

Figure 1 is a perspective view of a portable barbecue or similar article showing my new design.

I claim:

The ornamental design for a portable barbecue or similar article, substantially as shown.

JOHN SHIRLEY WARD.
